BACKGROUND OF THE INVENTION**(1) Field of the Invention****(2) Description of Related Art Including Information Disclosed Under 37 CFR 1.97 and 1.98**

The disclosure and prior art relates to crowd dispersing sprays and more particularly pertains to a new crowd dispersing spray for providing such a strong, repugnant smell that a crowd of people will attempt to avoid the spray.

BRIEF SUMMARY OF THE INVENTION

An embodiment of the disclosure meets the needs presented above by generally comprising a mixture including limburger cheese, rotten eggs, sulfur compounds having a smell of rotten food, rotten fish and rotten meat. The mixture is to be sprayed into a crowd of people to disperse the crowd.

There has thus been outlined, rather broadly, the more important features of the disclosure in order that the detailed description thereof that follows may be better understood, and in order that the present contribution to the art may be better appreciated. There are additional features of the disclosure that will be described hereinafter and which will form the subject matter of the claims appended hereto.

The objects of the disclosure, along with the various features of novelty which characterize the disclosure, are pointed out with particularity in the claims annexed to and forming a part of this disclosure.

BRIEF DESCRIPTION OF SEVERAL VIEWS OF THE DRAWING(S)

The disclosure will be better understood and objects other than those set forth above will become apparent when

2

consideration is given to the following detailed description thereof. Such description makes reference to the annexed drawings wherein:

FIG. 1 is a side view of a crowd dispersing composition according to an embodiment of the disclosure.

FIG. 2 is a schematic view of an embodiment of the disclosure.

DETAILED DESCRIPTION OF THE INVENTION

With reference now to the drawings, and in particular to FIGS. 1 and 2 thereof, a new crowd dispersing spray embodying the principles and concepts of an embodiment of the disclosure and generally designated by the reference numeral 10 will be described.

As best illustrated in FIGS. 1 and 2, the crowd dispersing composition 10 generally comprises a mixture of materials each having a highly objectionable odor component. The materials are blended together and the placed in a canister to allow the spraying of the mixture into a crowd of people to cause the crowd to scatter and disperse.

The composition includes a mixture comprising limburger cheese, rotten eggs, sulfur compounds having a smell of rotten food, rotten fish and rotten meat. The sulfur compounds may include hydrogen sulfide or an organosulfur compound.

More specifically, the mixture may contain by weight the following components:

30 18% to 22% limburger cheese;
18% to 22% rotten eggs;
18% to 22% hydrogen sulfide or an organosulfur compound;
18% to 22% rotten fish; and
35 18% to 22% rotten meat.

The components may be blended together in any conventional manner such that the mixture comprises a thin fluid or fine powder that may be easily sprayed under pressurized gas from a canister 12. Alternatively, a motorized sprayer 40 may be utilized instead of gas under pressure.

In use, the mixture may be deployed to police, security personnel and the like to be used for dispersing a crowd of people who are unlawfully gathered or otherwise pose a security risk. The mixture will not harm people, such as can 45 happen with pepper spray and other similar types of crowd control measures, but will cause people to avoid the smell. Moreover, the mixture may be removed from clothing and skin by conventional washing.

With respect to the above description then, it is to be 50 realized that the optimum dimensional relationships for the parts of an embodiment enabled by the disclosure, to include variations in size, materials, shape, form, function and manner of operation, assembly and use, are deemed readily apparent and obvious to one skilled in the art, and all 55 equivalent relationships to those illustrated in the drawings and described in the specification are intended to be encompassed by an embodiment of the disclosure.

Therefore, the foregoing is considered as illustrative only of the principles of the disclosure. Further, since numerous 60 modifications and changes will readily occur to those skilled in the art, it is not desired to limit the disclosure to the exact construction and operation shown and described, and accordingly, all suitable modifications and equivalents may be resorted to, falling within the scope of the disclosure. In 65 this patent document, the word "comprising" is used in its non-limiting sense to mean that items following the word are included, but items not specifically mentioned are not

excluded. A reference to an element by the indefinite article "a" does not exclude the possibility that more than one of the element is present, unless the context clearly requires that there be only one of the elements.

I claim:

1. A pressurized canister consisting essentially of:
18% to 22% limburger cheese;
18% to 22% rotten eggs;
18% to 22% hydrogen sulfide or an organosulfur compound;
18% to 22% rotten fish; and
18% to 22% rotten meat.
